PORTABLE FILTER DEMONSTRATION DEVICE
FOR SUCTION CLEANEREugene F. Martinec, East Cleveland, Ohio, assignor to
Health-Mor, Inc., Chicago, Ill., a corporation of Illinois

Application July 23, 1957, Serial No. 673,675

5 Claims. (Cl. 35—13)

This invention relates to a demonstration device and more particularly it pertains to a portable device for demonstrating the efficiency of a suction cleaner for filtering tobacco smoke and other fumes from the atmosphere.

It is frequently desirable in order to sell a suction cleaner to demonstrate the efficiency of the cleaner for filtering tobacco smoke and/or other fumes from the surrounding atmosphere. Where the cleaner is provided with a proper filter, such a demonstration may be carried out with considerable effectiveness.

Heretofore it has not been possible to demonstrate in a home the efficiency of a suction cleaner for filtering smoke from the atmosphere. The less efficient filters will remove dust and dirt having relatively large particle size. However, many filters readily pass particles of tobacco smoke with the air without separating the two as the smoke-filled air enters the filter. It is desirable that a simple means be provided for demonstrating in a home whether a cleaner has a filter which will remove smoke from air passed through the cleaner.

A device for demonstrating the efficiency of a suction cleaner for filtering tobacco smoke from the atmosphere is disclosed in my copending application, Serial No. 672,442, filed July 17, 1957. However, such a device is not readily portable and where the primary sales effort is conducted on a door-to-door basis, it is preferable that a filter demonstration device for a suction cleaner be composed of apparatus that is of minimum weight and bulk.

The device of the present invention includes a transparent collapsible hood which is placed over and around a suction cleaner for demonstration. The open end of the hood is secured tightly around the lower portion of the cleaner to achieve a substantially airtight connection. Tobacco smoke is introduced into the hood until the entire space around the cleaner is obviously filled with smoke. The cleaner is then turned on and the atmosphere within the hood is cleared of smoke in a very short period of time.

Accordingly, it is an object of this invention to provide a demonstration device that permits visual observation of a suction cleaner filtering tobacco smoke from the atmosphere.

It is another object of this invention to provide a portable demonstration device for showing the effectiveness of a suction cleaner for filtering smoke and/or other fumes.

It is another object of this invention to provide a portable demonstration device for demonstrating the smoke filtering advantages of a suction cleaner, which device is composed of minimum weight and bulk.

Finally, it is an object of the present invention to provide a demonstration device for a suction cleaner by which the foregoing objects and desiderata are obtained in a simple, effective and inexpensive manner.

These and other objects and advantages apparent to those skilled in the art from the following description and claims may be obtained, the stated results achieved and

2

described difficulties overcome by the discoveries, principles, apparatus, parts, combinations, subcombinations, and elements which comprise the present invention, the nature of which is set forth in the following statement, a 5 preferred embodiment of which—illustrative of the best mode in which applicant has contemplated applying the principles—is set forth in the following description, and which are particularly and distinctly pointed out and set forth in the appended claims forming part hereof.

Generally, the nature of the apparatus of the present invention may be stated as including a transparent collapsible hood having an open end adapted for insertion of a suction cleaner, the open end being provided with means for tightening the end of the hood around the housing of the cleaner in a substantially airtight manner, the hood having an outlet opening for the electric cord of the cleaner, the hood also having opening means for introducing tobacco smoke or the like into the hood around the cleaner, whereby subsequent operation of the cleaner removes the smoke-filled air from and returns smokeless air to the interior of the hood.

By way of example, a preferred embodiment of the apparatus of the present invention is shown in the accompanying drawings, wherein:

25 Figure 1 is an elevational view of the apparatus showing a suction cleaner mounted within a transparent collapsible hood, and showing an expanded bellows device for smoking a cigarette and injecting cigarette smoke into the interior of the hood;

30 Fig. 2 is an elevational view similar to Fig. 1 showing the hood filled with tobacco smoke, and showing the bellows in the contracted position;

35 Fig. 3 is a vertical sectional view taken on the line 3—3 of Fig. 4, showing the cleaner in elevation with a side wall portion broken away; and

Fig. 4 is a plan view of the assembly.

Similar numerals refer to similar parts throughout the several views of the drawings.

In Fig. 1 a demonstration device is generally indicated 40 at 1. It includes a transparent bag or hood 2 surrounding a suction cleaner 3, and a bellows 4 for smoking a cigarette 5 at one end and delivering tobacco smoke 6 (Fig. 2) at the other end into the hood 2.

The suction cleaner 3 includes an air inlet 7, an air filter 8, a porous filter backup member 9, and a plurality 45 of air outlets 10. In addition, the cleaner includes an electric cord 11, a perforated guard cap 12 detachably mounted on the air inlet 7, and a dolly 13 having a plurality of casters 14 on the underside thereof. The dolly 13 is composed of molded material such as rubber and the outer periphery includes at least one annular groove 15.

The hood 2 is composed of transparent material such as plastic or the like and is collapsible in structure. It 55 includes a cylindrical side wall portion 16 and a top wall portion 17 which is secured to the upper end of the cylindrical portion 16 at a seam 18. The lower end of the cylindrical wall portion 16 includes a hem portion 19 in which a draw cord 20 is disposed. In addition, the cylindrical wall portion includes a reinforced smoke inlet port 21 and a reinforced cord opening 22 on the opposite side thereof adapted to receive a resilient plug 23 through which the cord 11 extends and by which the opening 22 is plugged in an airtight manner. The cord plug 23 is apertured and slit at 24 for easy attachment to the cord 11.

The bellows 4 is composed of a resilient material such as rubber and is expandable and contractible from the elongated position of Fig. 1 to the contracted position of Fig. 2. One end of the bellows is provided with a tube 25 adapted for insertion into the smoke inlet 21 in the hood 2. The tube 25 is connected to a valve housing

26 which closes one open end of the bellows 4 and which contains a one-way smoke valve for passage of smoke from the bellows to the tube 25 and not vice versa. The other end of the bellows is provided with a tube or cigarette holder 27, in one end of which the cigarette 5 is inserted and the other end of which extends from a valve housing 28 which closes the other end of the bellows 4. Likewise, the valve housing 28 includes a one-way valve which permits the passage of smoke from the cigarette 5 into the bellows 4. In operation, the bellows 4 is handled manually so that upon expansion of the bellows 4 to an elongated position, smoke 6 is drawn from the lighted cigarette 5 into the interior of the bellows and upon contraction of the bellows, the smoke 6 is forced out of the bellows through the tube 25 into the interior of the hood and around the cleaner 3.

The demonstration device is operated by first attaching the guard cap 12 on the air inlet 7. The cap 12 has side apertures 12a to prevent the hood 2 from being sucked into the inlet 7 and blocking entry of air during the part of the demonstration when the cleaner is operated.

The open end of the hood 2 is then placed over the cleaner 3 to the position shown and the draw cord 20 is pulled tightly around the annular groove 15 of the dolly 13 until a snug, substantially airtight fitting between the lower end of the hood and the dolly is obtained. A knot is then tied in the end portions of the cord 20 as shown in Fig. 1. In addition, the electric cord 11 is extended through the cord opening 22, and the cord plug 23 is then placed upon the cord and inserted into the cord opening 22 to secure an airtight fitting between the cord 11 and the opening 22.

Thereafter the tube 25 of the bellows 4 is inserted into the smoke inlet port 21 and the cigarette 5 is inserted into the cigarette holder 27 at the opposite end of the bellows 4. At this stage of the demonstration the cleaner 2 remains inoperative while the cigarette is smoked by expanding and contracting the bellows manually until the interior of the hood 2 is completely filled with smoke 6 as shown in Fig. 2. The smoke of one cigarette 5 is usually sufficient for this purpose.

The cleaner 3 is then turned on so that the entire atmosphere within the hood 2 and around the cleaner is drawn into the cleaner through the air inlet 7. As the smoke-filled air passes through the filter 8, the smoke and air are separated and smokeless air is exhausted from the cleaner through the air outlets 10 to the hood 2. In order to separate the smoke from the air, the filter 8 preferably has air passages of such size that air passes but smoke particles do not and the smoke particles are thereby filtered out of the air.

Inasmuch as the hood 2 is transparent, the foregoing operation is clearly visible from the beginning of the operation when the smoke is introduced into the space within the hood and until the cleaner 3 is turned on to clear the atmosphere and restore it to clear visibility. By providing a filter 8 with passages sufficiently small to pass air but not particles of tobacco smoke, the smoke and air are separated within the cleaner by the filter so that smokeless air is exhausted into the hood 2.

Although the bellows 4 is an expedient way of introducing smoke into the hood 2, it may be introduced by other means such as the operator smoking a cigarette and blowing the smoke orally into the hood through the opening 21.

The transparent hood 2 of the present invention provides an expedient means for demonstrating visually the effectiveness of the suction cleaner 3 for filtering cigarette smoke, noxious fumes, and the like from the atmosphere. The hood 2 contains the smoke in a small concentrated area around the cleaner and when the smoke-filled air is returned as clean smokeless air, the efficiency of the cleaner as an air filtering device is readily apparent.

ent. By providing a collapsible, transparent, portable hood, the demonstration may be made more readily to a greater number of prospective customers.

The improved portable demonstration device can be used not only for an effective home demonstration of the efficiency of a cleaner in filtering smoke from air, but it may be used for home demonstration of the effectiveness of various filter papers or other filtering media used in a suction cleaner. For instance, the conical air filter 8 may be formed of paper filter material, and if such filter paper is not effective in filtering smoke, recirculation of a smoke-filled atmosphere within the hood 2 upon operation of the device will leave a visible smoke-contaminated atmosphere within the hood, demonstrating lack of filter efficiency. The demonstration device may be used in this manner to demonstrate the efficiency of different filtering materials provided as filters 8 for the cleaner 3.

Also, the device may be used to compare the operation of different cleaners with the same or different filter material. A particular cleaner with a particular filter 8 therein which is very efficient in completely filtering all smoke from the smoke-filled atmosphere within the hood 2 may be demonstrated with the device. Then another type of cleaner may be placed within the hood 2 having its usual filter and the device operated. If the filter in the second cleaner is not efficient in completely filtering all smoke from smoke-contaminated air recirculated through the cleaner, the inefficiency of the second cleaner and its filter will be visually apparent.

An advantageous and extraordinary use of a suction cleaner may be explained and appreciated by operating the improved portable demonstration device in the home. Thus, operation of the device to visually demonstrate that a cleaner and its filter completely filter all smoke from smoke-laden air passed through the cleaner enables a home owner to understand that if the cleaner is placed in a closed, smoke-filled room and operated for a sufficient period of time to circulate all of the air in the room through the cleaner, the smoke in the room will be filtered and removed from the air.

Such a showing is important since normally the removal of annoying smoke from the atmosphere in a room or private or public gathering place requires either prolonged airing or the installation and use of special air-conditioning equipment.

In the foregoing description certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction shown.

Having now described the features, constructions and principles of the invention, the characteristics of the new portable filter demonstration device for suction cleaner, and the advantageous, new and useful results provided; the new and useful discoveries, principles, parts, elements, combinations, subcombinations, structures and arrangements, and mechanical equivalents obvious to those skilled in the art are set forth in the appended claims.

I claim:

1. Portable demonstration equipment for visually demonstrating the efficiency of a suction cleaner for filtering smoke from smoke-containing air drawn through the cleaner, including a collapsible hood having a transparent side wall forming an open end adapted to enclose a portion of the cleaner including the inlet and outlet means, means at the open end of the side wall for securing the side wall in airtight enclosing relation to the cleaner outer surface; means including a smoke inlet in the hood for introducing smoke into the hood, and means

for operating a cleaner with a portion so enclosed to withdraw smoke-filled air through the cleaner inlet means from and to return smokeless air through the cleaner outlet means to the interior of the hood.

2. Portable demonstration equipment for visually demonstrating the efficiency of a suction cleaner for filtering smoke from smoke-containing air drawn through the cleaner, including a collapsible hood having a transparent side wall and an end wall at one end of the side wall, the side wall having an open end adapted to enclose a portion of the cleaner including the inlet and outlet means, means at the open end of the side wall including a draw cord for securing the side wall in airtight enclosing relation to the cleaner outer surface, a smoke inlet in the hood for introducing tobacco smoke into the hood, and means for operating a cleaner with a portion so enclosed to withdraw smoke-filled air through the cleaner inlet means from and to return smokeless air through the cleaner outlet means to the interior of the hood.

3. Portable demonstration equipment for visually demonstrating the efficiency of a suction cleaner for filtering smoke from smoke-containing air drawn through the cleaner, including a collapsible hood adapted to enclose a portion of the cleaner including the inlet and outlet means, the hood including a side wall and an end wall closing one end of the side wall, at least one of the side and end walls being transparent, the side wall having a hemmed portion forming an open end, a draw cord in the hemmed portion of the side wall adapted to secure the hemmed portion in airtight enclosing relation to the cleaner outer surface, a smoke inlet in the hood, and means for operating a cleaner with a portion so enclosed to withdraw smoke-filled air through the cleaner inlet means from and to return smokeless air through the cleaner outlet means to the interior of the hood.

4. Portable demonstration equipment for visually demonstrating the efficiency of a suction cleaner for filtering smoke from smoke-containing air drawn through the cleaner, including a collapsible hood having a transparent substantially cylindrical side wall and an end wall

at one end of the side wall, the side wall having an open end adapted to enclose a portion of the cleaner including the inlet and outlet means, means at the open end of the side wall for securing the side wall in airtight enclosing relation to the cleaner outer surface, the hood having a smoke inlet, bellows means detachably connected with said smoke inlet for introducing smoke into the hood, and means for operating a cleaner with a portion so enclosed to withdraw smoke-filled air through the cleaner inlet means from and to return smokeless air through the cleaner outlet means to the interior of the hood.

5. Portable demonstration equipment for visually demonstrating the efficiency of a suction cleaner for filtering smoke from smoke-containing air drawn through the cleaner, including a collapsible hood having a transparent substantially cylindrical side wall and an end wall at one end of the side wall, the side wall having an open end adapted to enclose a portion of the cleaner including the inlet and outlet means, means at the open end of the side wall for securing the side wall in airtight enclosing relation to the cleaner outer surface, a perforated guard cap detachably mountable on the cleaner air inlet means and adapted to hold the side wall of the hood from being sucked into said inlet means, the hood having a smoke inlet, bellows means detachably connected with the smoke inlet for introducing smoke into the hood, and means for operating a cleaner with a portion so enclosed to withdraw smoke-filled air through the cleaner inlet means from and to return smokeless air through the cleaner outlet means to the interior of the hood.
